(57) **CLAIM**

The ornamental design for a sterilization tray, as shown and described.

DESCRIPTION

FIG. 1 is a perspective view of a tub component of a sterilization tray;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a perspective view of a lid component of the sterilization tray;

FIG. 9 is a top view thereof;

FIG. 10 is a bottom view thereof;

FIG. 11 is a left side view thereof;

FIG. 12 is a right side view thereof;

FIG. 13 is a front view thereof;

FIG. 14 is a rear view thereof;

FIG. 15 is a perspective view of the tub and lid components of the sterilization tray assembled together;

FIG. 16 is a top view thereof;

FIG. 17 is a bottom view thereof;

FIG. 18 is a left side view thereof;

FIG. 19 is a right side view thereof;

FIG. 20 is a front view thereof; and,

FIG. 21 is a rear view thereof.

The broken lines depict portions of the sterilization tray that form no part of the claimed design.

1 Claim, 19 Drawing Sheets
